UNITED STATES PATENT OFFICE.

RALPH B. CARTER, OF HAWORTH, NEW JERSEY.

PUMP.

1,410,994.

Specification of Letters Patent. Patented Mar. 28, 1922.

Application filed February 9, 1918. Serial No. 216,363.

To all whom it may concern:

Be it known that I, RALPH B. CARTER, a citizen of the United States, residing at Haworth, in the county of Bergen and State 5 of New Jersey, have invented certain new and useful Improvements in Pumps, of which the following is a full, clear, and exact specification, such as will enable others skilled in the art to which it appertains to 10 make and use the same.

This invention relates to improvements in power-operated pumps, and is designed to obviate one source of trouble in pumps, as at present constructed, due to the accumulation of air in the pump, in such quantity 15 and under such conditions as to constitute what is known as a "air-block", which will stop the pumping of the fluid to be handled.

My invention is shown applied to a 20 double-acting hydraulic pump, which may be operated from any suitable source of power but which is particularly adapted for operation by a motor which may be automatically started and stopped, in connection 25 with domestic or similar water supply systems, wherein air and water are together pumped to a receiving tank, from which the water, under pressure of the air in the storage tank, may be led, as desired, to 30 any part of the premises.

In such water supply plants, it is desirable that the pumping means shall be thrown into operation automatically when the water in the storage tank recedes to a 35 certain level, and cut out of operation when the water in the tank has reached a certain desired quantity. Thus it is necessary that the pump shall not be interrupted by the presence of an "air-block", as above referred 40 to, as this would require the presence of an attendant to look after its operation.

The condition of "air-block", above referred to, may arise in any ordinary hydraulic pump, but a pump which has an air 45 inlet from the exterior atmosphere, and is designed to pump both air and water to place the latter under compression by the air, in a storage tank, is particularly subject to such a condition.

It will be recognized therefore, that such 50 improvements as have the effect of removing the causes of such "air-blocks" are highly useful, for it is evident, that, unless there is a complete absence of "air-block", 55 or means provided whereby, as soon as they occur, they can be immediately and auto-

matically overcome, the term "automatic", as applied to such pumps, is a misnomer since an attendant will be required to again start the pump in operation. 60

The principal object of my present invention is to prevent leakage of air through the discharge valves from the discharge chamber to and into the pump chambers.

Another object of my invention is to 65 provide means for accomplishing the above stated object in pumps especially designed to afford simplicity in construction and accessibility to the parts, without requiring the removal of the connections to the storage 70 tank.

Another object of my invention is to provide means for accomplishing the above stated object in forms of pumps now used, without requiring any material change in 75 structure.

Other objects, such as economy in manufacture and durability in construction, will be apparent from the following description, taken in connection with the accompanying 80 drawings, in which:

Fig. 1 is a vertical central section, and Fig. 2 is a vertical transverse section on line 2—2 of Fig. 1.

Referring to the construction illustrated, 85 B represents the pump casing, formed centrally with an inwardly projecting casting C, which is longitudinally bored to form a piston cylinder D, wherein reciprocates a piston E, which is actuated, through the piston rod F, from any suitable source of power. The ends of the casing B are closed by the heads G, H, providing respectively, the pump chambers I, J. Formed at the lower portion of the casing B is a suction 90 chamber K, said suction chamber being in communication with a water inlet M, which may be connected to a well or other source of water supply. Secured to the upper portion of the casing B is a discharge chamber 100 N, formed by the bonnet O, which chamber, through the passageway, P, connects with an air chamber P'. Suction valves Q, Q', are provided in passageways leading from the suction chamber K, to the pump chambers I, J, and discharge valves R, R', are located in passageways leading from the pump chambers I, J, to the discharge chamber N. 105

In the head G, is an air inlet, provided 110 with a check valve, through which air may be taken from the exterior atmosphere.

A threaded opening T is adapted to receive a discharge pipe leading to a storage tank, (not shown), wherein water and air under compression are received, to be drawn 5 on as occasion requires. It will be understood that such pipe will be provided with a check valve to prevent the return flow of water from the storage tank.

The operation of the pump as thus far described needs no particular description except to state that on the reciprocating movement of the piston F, water is drawn from the suction chamber K, (to which it is admitted through the opening M), through the 10 suction valves Q, Q', into the pump chambers I, J, and, in company with air from the exterior atmosphere, is expelled, under action of the piston F, through the discharge valves R, R', into the discharge chamber N, 15 and thence through the discharge opening T, to the storage tank (not shown).

No novelty is claimed herein for the pump as thus far described. I will now describe my invention as applied to such pump.

20 As such pumps have been heretofore constructed, from the opening T a passageway T' has led upwardly meeting approximately flush with or lower than the valve deck of the discharge chamber N, as indicated by the dotted lines in the drawings, and the result of such construction has been, as the entrance to passageway T' has been level with or lower than the valve deck (indicated at U), the water in the discharge chamber N 25 has been free to completely drain therefrom and the valves R, R', have not been water-sealed. Thus the air, which is under compression, in the discharge chamber, has been free to leak past the discharge valves, back 30 and into the pump chambers, there to cause churning of the fluid by the piston, and eventually result in an "air-block," as I 35 have before described.

Now, in carrying out my invention, instead of having an opening to the passageway, T', and outlet T, approximately at the height of the valve deck U, I provide means whereby the water is taken off at a higher 40 level than the valve deck, one form of which 45 means is clearly shown in the drawings, comprising a threaded portion V, in an opening in the casing B wherein I place the threaded lower end of a take-off member, or standpipe, indicated at V', the upper end 50 of which will preferably normally project into the air chamber P', the result of which 55 construction is that the water passing out through the passageway T', and discharge opening T, has to first enter and pass 60 through the take-off member V'. It will thus be seen that as all the water passing from the discharge chamber must rise to the top of, and pass into and through the take-off member V', it will be impossible, in the 65 operation of the pump, to drain the valve

deck of the discharge chamber. On the contrary, not only the discharge chamber N but the air chamber P' will normally be filled with water to the level of and above the top of the take-off member V'. Thus, 70 the valves R, R', will always be water-sealed by a solid body of water standing on the valve deck in that chamber. Since the air will rise above the water, and the water, at the lower level, is impervious to penetration 75 by the air, it will be impossible for air in the air chamber or discharge chamber to seep through and into the pump chamber.

It has been pointed out above that it is desirable that pumping apparatus of the 80 character herein referred to shall be completely automatic. It is also desirable, that, when once installed, it shall not require taking down or taking apart, or call for the work of expert mechanics. It is desirable, 85

however, that access may be had occasionally to certain of the moving parts, for instance for the renewal of the rubber disks of the valves. When they require looking after, in order to get access to the valve deck 90

of the discharge chamber, all that is required is that the bolts securing the bonnet to the pump casing be loosened, whereupon the bonnet and air chamber can be bodily lifted clear of the valves, exposing the latter to 95

view, for examination or repair or renewal of parts, as may be required. The same is true of the suction valves Q, Q'. By loosening the bolts securing the suction chamber 100 to the pump casing, the entire suction chamber with the valves, may be dropped out of position, for inspection and renewal of parts. Thus it will be seen that the piping leading to the storage tank may remain in 105 place and undisturbed. I provide in such a structure, having the desired features of accessibility of parts, means whereby the valves in the discharge chamber are water-sealed by a continually present body of 110 water in the discharge chamber. This, I regard as a radical improvement in the art.

I desire it to be understood that I do not wish to confine myself to the precise details of construction and arrangement of the invention as herein set forth, as modification 115 and variation may be made without departing from the spirit of the invention as defined by the appended claims.

What I claim is:

1. In a hydraulic pump, the combination 120 of a valve-deck having discharge valve openings, said deck also having a passageway leading to the pump outlet, and a standpipe communicating with said passageway having an inlet in its free end above the 125 level of the valves in said valve-deck.

2. In a hydraulic pump, the combination 130 of a valve-deck having discharge valve openings, said deck also having a passageway leading to the pump outlet, an air

- chamber superposed above said valve-deck, and means communicating with said passageway and extending into said air chamber, for receiving water at a point higher than said discharge-valve openings, and discharging the same through said passageway.
3. In a combined air and water pump, the combination with a valve-deck having discharge valves and an opening leading to the pump outlet, of means connected with said opening for raising the water to a higher level than the valve-deck and water-sealing said valves and drawing water at said level for discharge from said outlet, thereby preventing a back-flow of air into the pump-chamber.
4. In a combined air and water pump, the combination of a pump-chamber, a discharge chamber, a valve-deck between said chambers having discharge valve openings, said pump having suction inlets for air and water, and a discharge outlet extending from said valve-deck, means for pumping fluid including water and air from the pump-chamber into the discharge chamber, and a stand-pipe connected to said outlet from said valve-deck and extending into the discharge chamber for raising the level of water around the stand-pipe and above the dis-
- charge valve openings, thereby preventing a back-flow of air into the pump-chamber, and for receiving fluid for discharge from said outlet.
5. In a combined air and water pump, the combination with a valve-deck having discharge valves and a passage therefrom extending thereunder to the pump outlet, of a stand-pipe connected to said passage in said valve-deck and having a free end extending into the discharge chamber for raising the level of water above the discharge valves, thereby preventing a back-flow of air into the pump-chamber.
6. In a combined air and water pump, the combination of a pump-chamber, a discharge chamber, a valve-deck between said chambers having discharge valve openings, an opening therein extending under the same to the pump outlet, an air chamber having free communication with the discharge chamber, a stand-pipe connected to the opening in said valve-deck leading to the pump outlet, said stand-pipe having a free end extending into the air chamber for raising the level of water above the discharge valves and preventing a back-flow of air into the pump-chamber.

RALPH B. CARTER.
